Patented Dec. 8, 1959

186,816

POWER-BLOWER UNIT FOR SPRAYERS

William J. Besler, Piedmont, Calif.

Application September 30, 1957, Serial No. 47,930

Term of patent 14 years

(Cl. D31—3)

FIG. 1

Des. 186,816

PAGE 2

FIG. 2

FIG. 3

FIG. 4

FIG. 5

Figure 1 is a front and top perspective view of the power-blower unit for sprayers, showing my new design;

Figure 2 is a front elevational view thereof;

Figure 3 is an elevational view of the right side;

Figure 4 is a rear elevational view; and

Figure 5 is an elevational view of the left side.

I claim:

The ornamental design for a power-blower unit for sprayers, as shown.
